UNITED STATES PATENT OFFICE.

EARL PARSONS, OF PHILADELPHIA, PENNSYLVANIA.

BRACKET.

1,391,495.

Specification of Letters Patent. Patented Sept. 20, 1921.

Application filed September 18, 1919, Serial No. 324,410. Renewed August 20, 1921. Serial No. 493,918.

To all whom it may concern:

Be it known that I, EARL PARSONS, a citizen of the United States, residing at Philadelphia, in the county of Philadelphia and 5 State of Pennsylvania, have invented certain new and useful Improvements in Brackets, of which the following is a specification.

One object of my invention is to provide 10 an improved wardrobe bracket which can be easily attached within a closet, wardrobe, trunk or other cabinet for the purpose of suspending garment hangers with garments thereon, and which will include a portion 15 movable out of the confines of said cabinet to permit the garments to be separated to such extent as to allow ready access thereto.

Another object is to so construct my improved bracket that said extensible portion 20 can be freely moved inwardly and outwardly without accidentally jamming or displacing the garment hangers.

A further object is to make my improved bracket of a simple and durable construction and so that it can be easily manipulated. 25

These objects, and other advantageous ends which will be described hereinafter, I attain in the following manner, reference being had to the accompanying drawings 30 in which—

Figure 1 is a perspective view showing my improved bracket in position within a cabinet and showing a portion extended beyond the confines of the cabinet to permit 35 the garments to be slid outwardly into widely separated positions.

Fig. 2 is a perspective view showing the extensible portion moved inwardly so that the garments and the bracket are entirely 40 within the confines of the cabinet.

Fig. 3 is a fragmentary sectional elevation showing my improved bracket with said portion in an extended position,

Fig. 4 is a fragmentary enlarged plan 45 view of certain of the elements of my invention,

Fig. 5 is a transverse section taken on the line 5—5 of Fig. 4,

Fig. 6 is a section taken on the line 6—6

50 of Fig. 4,

Fig. 7 is a section taken on the line 7—7 of Fig. 6, and

Fig. 8 is an end view of the extensible portion.

55 Referring to the drawings, 9 represents a

cabinet having a back 10 and a shelf or overhead structure 11. A hanger 12 is secured to the structure 11 and depends therefrom and is provided with a hooked end 13. A plate 14 is secured adjacent the back 60 board 10 and provides a support for the end of a bar 15; the forward end of the bar being secured to the hooked end 13 of the hanger 12. The bar 15 is grooved at its uppermost part to provide a channel 16. A 65 tube 17 telescopically slides on the bar 15 and has a slot 18 in its bottom through which the hooked end 13 of the hanger 12 projects. This slot 18 stops short of the end 19 of the tube 17 and the surface forming 70 the innermost end of said slot, during the outward movement of the tube 17, engages the hooked end 13 of the hanger 12 and limits the outward movement of said tube 17 in a manner clearly shown in Fig. 3. The 75 forward end of the tube 17 has an annularly extending flange or head 20 for a purpose hereinafter described.

The tube 17 at its rear end has a lip 21 which is bent at an incline; the free end of 80 the lip extending within the channel 16. Garment hangers 22 can be suspended on the tube 17 and on the bar 15, as shown in Fig. 1, and the inclined lip 21, when the tube 17 is pushed inwardly, acts as a lifter to 85 lift the hangers 22 from the bar 15 so that as the tube 17 moves inwardly the hangers 22 will position themselves on the tube 17, as shown in Fig. 2. This action is also illustrated in Fig. 6; the cross section of 90 the hangers 22 being shown in dot-and-dash lines. By this arrangement the tube 17 can be freely moved inwardly and outwardly without jamming or improperly displacing the garment hangers 22 and when the tube 17 is moved outwardly any of the hangers 95 can be manually slid outwardly upon the tube 17 as is obvious from the construction illustrated.

The head 20 serves to prevent the garment hangers 22 from slipping off the forward end of the tube 17 during the sliding movement of said tube.

While I have described my invention as taking a particular form, it will be understood that the various parts of my invention may be changed without departing from the spirit thereof, and hence I do not limit myself to the precise construction set forth, but consider that I am at liberty to 100 105 110

make such changes and alterations as fairly come within the scope of the appended claims.

Having thus described my invention, what I claim as new and desire to secure by Letters Patent is:—

1. A device of the character described including two supporting members, one slideable within the other, the inner member having a longitudinal channel, the outer member having a lip at its end depending into said channel, said lip having its upper surface inclined from a position above the top to a position below the top of said channel.
- 10 2. A device of the character described including two supporting members, one slideable within the other, the inner member hav-

ing a longitudinal channel, the outer member having an integral lip bent downwardly at an incline and extending into said chan- 20 nel.

3. A bracket of the character described including a bar having a channel extending in the direction of its length; means for supporting said bar; and a tube slideable on 25 said bar and having a lip bent at an incline into said channel.

In testimony whereof I have signed my name to this specification in the presence of two subscribing witnesses.

EARL PARSONS.
